UNITED STATES PATENT OFFICE.

EARLE C. MCKINNIE, OF CHICAGO, ILLINOIS, ASSIGNOR TO NATIONAL X-RAY REFLECTOR CO., OF CHICAGO, ILLINOIS, A CORPORATION OF ILLINOIS.

LIGHTING-FIXTURE.

1,295,778.

Specification of Letters Patent. Patented Feb. 25, 1919.

Application filed June 20, 1917. Serial No. 175,776.

To all whom it may concern:

Be it known that I, EARLE C. MCKINNIE, a citizen of the United States, residing at Chicago, in the county of Cook and State 5 of Illinois, have invented a certain new and useful Improvement in Lighting-Fixtures, of which the following is a specification.

My invention relates to that class of fixtures which are termed semi-indirect, and 10 has for its object to provide means to reflect and diffuse some of the direct light rays and illuminate a bowl surrounding the reflector, which reflects the light rays to the ceiling in this manner, highly increasing the 15 effectiveness and enhancing the appearance of the fixture as a whole.

My means of accomplishing the foregoing objects, may be more readily understood by 20 having reference to the accompanying drawings, which are hereunto annexed and are a part of this specification, in which:

Figure 1 is a vertical sectional view of 25 a fixture embodying my invention.

Fig. 2 is a modified form of the same.

Similar reference numerals refer to similar parts throughout the entire description.

As shown in Fig. 1, my fixture consists 30 of a diffuser ring 3, formed of opal glass and so shaped as to receive the direct light rays from the electric light bulb 4, and reflect them in a diffused manner. As clearly 35 shown by the lines in said figure, this ring 3 is supported by an annular member 5, which is hung from the ceiling by chains 6, secured to a canopy 7, of the usual construction. The member 5, supports a bowl 8, of translucent glass, which surrounds the diffuser ring 3, and a reflector 9, which is 40 carried by the diffuser ring 3, and is designed to reflect the rays of light from the bulb 4, upwardly to the ceiling whence they are redirected to the working plane. It may 45 be found desirable in some instances to construct the diffuser ring, as shown in Fig. 2 in which it is provided with an inner wall 12 of opal glass and an outer wall 13, which may be vertical or slightly flaring and which has a mirrored surface adapted to receive the diffused light rays and reflect them upon

the bowl 8, and thus illuminate it. Where 50 the reflector 9, is made of glass, it may in some cases be expedient to blow the diffuser ring integral with it, in which case it would not be silvered beyond the point where it joins the diffuser ring. In some cases it 55 may be desirable to omit the annular member 5, and support the fixture from the diffuser member, thus producing an all glass fixture.

Having described my invention what I regard as new and desire to secure by Letters Patent is:

1. A semi indirect lighting fixture comprising the combination with a source of light, of a reflector adapted to direct the 65 light rays upwardly against the ceiling, a diffuser ring of glass supporting said reflector, said ring being shaped so as to reflect a portion of the direct rays of light downwardly and diffuse them, an annular 70 member which supports said diffuser ring, and a translucent glass bowl carried by said member, said bowl surrounding the diffuser ring and reflector.

2. A semi indirect lighting fixture comprising the combination with a source of light, of a reflector adapted to direct the light rays upwardly against the ceiling, a diffuser ring of glass supporting said reflector and formed integral therewith, said 80 ring being shaped so as to reflect a portion of the direct rays of light downwardly and diffuse them, an annular member which supports said diffuser ring, and a translucent glass bowl carried by said member, said bowl 85 surrounding the diffuser ring and reflector.

3. A semi indirect lighting fixture comprising the combination with a source of light, of a reflector adapted to direct the light rays upwardly against the ceiling, a 90 diffuser ring of glass supporting said reflector, said ring being shaped so as to reflect a portion of the direct rays of light downwardly and diffuse them, a translucent bowl surrounding the diffuser ring and reflector.

4. A semi indirect lighting fixture comprising the combination with a source of

light, of a reflector adapted to direct the light rays upwardly against the ceiling, a diffuser ring of glass supporting said reflector, and formed integral therewith, said 5 ring being shaped so as to reflect a portion of the direct rays of light downwardly and

diffuse them, a translucent bowl surrounding the diffuser ring and reflector.

In testimony whereof, I have signed the foregoing specification.

EARLE C. McKINNIE.
